(57) **CLAIM**

I claim the ornamental design for a tote bag with cover flap and divided interior, as shown and described.

DESCRIPTION

FIG. 1 is a front, side and top perspective view of the tote bag with cover flap and divided interior, showing the tote bag fully expanded and open;

FIG. 2 is a front, side and top perspective view of the tote bag with cover flap and divided interior, showing the tote bag fully compressed and closed;

FIG. 3 is a top plan view of the tote bag with cover flap and divided interior;

FIG. 4 is a rear view of the tote bag with cover flap and divided interior;

FIG. 5 is a side elevation view of the tote bag with cover flap and divided interior;

FIG. 6 is front view of the tote bag with cover flap and divided interior;

FIG. 7 is bottom view of the tote bag with cover flap and divided interior;

FIG. 8 is top plan view of the tote bag with cover flap and divided interior, showing the tote bag fully expanded and open; and,

FIG. 9 is top plan view of the tote bag with cover flap and divided interior, showing the tote bag fully expanded and open.

The broken lines representing stitching are part of the claimed design.
